UNITED STATES PATENT OFFICE.

RAYMOND WARRENDER, OF RICHMOND HILL, NEW YORK.

DESIGN FOR LITHOGRAPHED PAPER.

41,224.

Specification for Design.

Patented Mar. 7, 1911.

Application filed October 12, 1910. Serial No. 586,929. Term of patent 3½ years.

To all whom it may concern:

Be it known that I, RAYMOND WARRENDER, a citizen of the United States, residing at No. 275 Lincoln avenue, Richmond Hill, in the county of Queens and State of New York, have invented a new, original, and ornamental Design for Lithographed Paper, of which the following is a specification, reference being had to the accompanying drawing, forming part thereof.

The figure is a plan view of a portion of paper illustrating my design.

I claim:

The ornamental design for lithographed paper, as shown.

RAYMOND WARRENDER.

Witnesses:

E. S. TUTTLE,
R. J. MEEHAN.

Copies of this design may be obtained for five cents each, by addressing the "Commissioner of Patents, Washington, D. C."
